JAR CLOSURE

Henry Sieverling, Burdett, Kans.

Application August 30, 1933, Serial No. 687,506
Renewed April 5, 1935

1 Claim. (Cl. 215—92)

This invention appertains to new and useful improvements in receptacle closures, and more particularly to a novel closure and seal for jars, particularly of the fruit type.

- 5 The principal object of the present invention is to provide a closure for jars wherein clamp means of simple construction is employed for effecting a tight application of the jar top to insure as near perfect a seal as possible.
- 10 During the course of the following specification, other important objects and advantages of the invention will become apparent to the reader.

In the drawings:—

15 Figure 1 represents a side elevational view of a jar equipped with the novel closure.

Figure 2 represents a fragmentary side elevational view of a jar equipped with the novel closure, taken from a point approximately 90° spaced from the position from which Figure 1 is viewed.

20 Figure 3 represents a top plan view of the novel closure on a jar.

Figure 4 represents a top plan view of the cap.

Figure 5 represents a fragmentary vertical sectional view taken substantially on line 5—5 of Figure 1.

25 Figure 6 represents a perspective view of the clamp.

Figure 7 represents a plan view of the stamping from which the clamp is formed.

30 Figure 8 represents a pattern of the cam shoulder on the jar neck.

Figure 9 represents a sectional view fragmentarily showing the clamp with an opening instead of the depression.

35 Referring to the drawings wherein like numerals designate like parts, it can be seen in Figure 1 that numeral 5 represents the jar proper, while numeral 6 represents the neck portion which is provided with the outstanding circumferentially extending shoulder 7 provided on its bottom side with cam surfaces 8.

40 Numeral 9 represents the cap which is provided with a depending circumferentially extending apron 10 which snugly fits the upper portion of the neck 6 and rests upon the packing ring 11, which ring is positioned upon the shoulder 7, it being understood that when the apron 10 is resting upon the packing ring 11, there exists a space between the upper end of the neck 6 and the bottom of the cap 9. The neck 6 is preferably slightly tapered upwardly and the interior of the apron 10 is correspondingly shaped so that a more or less wedging action of the apron with the neck will be obtained.

The clamp is generally referred to by numeral 12 and consists of an elongated strip 13 of metal provided with an enlarged central portion denoted by numeral 14 which, as shown in Figure 9, can be provided with a circular opening 15, 5 or as shown in Figure 6, may be provided with a raised portion 16 resulting from an indentation impressed from the bottom side of the strip.

The end portions of the strip 13 are bent downwardly to provide leg portions 17 and these leg portions are bent inwardly at their lower ends to provide foot portions 18. As is clearly shown in Figure 5, the leg portions extend downwardly along the sides of the apron 10 and the shoulder 7, while the foot portions 18 engage under the 15 shoulder and against the cam surfaces 8. Finger engaging lugs 19—19 are provided on the leg portions 17, the lugs being located on alternate edge portions of the legs, as in the manner substantially shown in Figure 7, which is a pattern 20 view of the clamp stamping.

Obviously, in order to place the clamp 12 properly upon the cap 9, the same is slid over the cap until the boss 20 is properly seated in the pocket 16 or in the recess of the form shown in 25 Figure 9 and denoted by numeral 15. While the clamp is thus being positioned on the boss 20, the foot portions 18 are engaging under the shoulder 7 and obviously, by engaging the fingers against the lugs 19 and effecting a rotary motion 30 of the clamp on the cap, the foot portions 18 will ride the cam surfaces 8 and cause a drawing down motion of the clamp, which obviously binds the cap 9 to the neck 6 with its apron 35 against the packing 11, producing a hermetical seal.

While the foregoing specification sets forth the invention in specific terms, it is to be understood that numerous changes in the shape, size and materials may be resorted to without departing from 40 the spirit and scope of the invention as claimed hereinafter.

Having described the invention, what is claimed as new is:—

A closure clamp for jars having cam shoulders 45 on the necks thereof, comprising a U-shaped member provided with inturned extremities on the leg portions thereof, said member being stamped from sheet metal to provide a lateral extension on one vertical edge of each leg, said extensions 50 being bent backwardly in oblique relation to the outside of their corresponding leg portions to provide finger engaging means.

HENRY SIEVERLING.
